TYPIST'S COPYING GAUGE

Samuel Ford, Denver, Colo.

Application May 25, 1936, Serial No. 81,626

4 Claims. (Cl. 120—34)

This invention relates to a copy holder for typists and has for its principal object the provision of a neat, efficient compact foldable device which will hold the material to be copied in an 5 easily visible position and which will successively indicate the line to be copied as the copying progresses.

Another object of the invention is to provide an 10 efficient mechanism which can be rapidly operated by finger pressure to move the indicating gauge accurately along the work and to provide a gauge which will indicate line lengths and line 15 positions on the sheet being copied so that an exact duplicate may be made.

Other objects and advantages reside in the 20 detail construction of the invention, which is designed for simplicity, economy, and efficiency. These will become more apparent from the following description.

In the following detailed description of the 25 invention reference is had to the accompanying drawing which forms a part hereof. Like numerals refer to like parts in all views of the drawing and throughout the description.

In the drawing:

Fig. 1 is a perspective view of the improved 30 copy holder, as it would appear ready for use.

Fig. 2 is a rear view thereof with the supporting arms or legs in the folded position.

Fig. 3 is an enlarged detail section taken on 35 the line 3—3, Fig. 1.

Fig. 4 is an enlarged side elevation of the line 40 spacer.

The invention consists of a backing board or 45 plate 10, turned outwardly along its lower edge to form a projecting shelf 11. On the back of the plate 10, adjacent each vertical edge thereof, a toothed rack bar 12 is positioned. The upper extremities of the rack bars 12 support hinge 50 arms 13 and the latter support a paper clamp bar 14 across the upper front of the plate 10. The clamp bar 14 is constantly pressed against the plate by means of tension springs 15 acting upon lever extremities on the hinge arms 13.

The lower extremities of the rack bars 12 are 55 formed into bracket members 16, to each of which a supporting arm 17 is hinged. The outer extremities of the arms are provided with rubber cushions 19.

At their bottoms, the rack bars 12 terminate 60 in legs 20 provided with suitable rubber cushions 21. The weight of the device rests upon the legs 20 and it is supported in an inclined vertical position by the arms 17 which project rearwardly at an upward angle.

The brackets 16 also provide a support for hingedly supporting a pair of side arms 22 which extend forwardly of the shelf 11 and terminate in a line-spacing bar 23. The line-spacing bar extends across the plate 10 immediately in front of the shelf 11. A coil spring 24 supports the line-spacing bar in the raised position until depressed with the finger. Two stop bosses 25 and 26 are formed on each of the bracket members 16 to limit the upward and downward arc of movement of the line-spacing bar. A rod 27 is connected with one of the side arms 22 and extends upwardly therefrom alongside of, and parallel to, the rack bar 12.

A line gauge plate 28 extends entirely across the front of the plate 10, and terminates at its extremities in terminal brackets 29 which overlap the edges of the plate 10 to maintain the gauge 28 in place thereon. A pinion shaft 30 extends across the back of the plate 10 between the brackets 29 and carries two pinions 31 fixedly secured thereon. The pinions 31 engage the teeth of the rack bars 12 and, since they are fixed to the shaft 30 constantly hold the gauge 28 in a horizontal position.

A lever 32 is rotatably mounted on one extremity of the pinion shaft 30. The lever 32 has an opening for the passage of the rod 27. This opening is of a size to allow the rod 27 to slide freely through the lever 32 when the latter is positioned at right angles to the rod but when the lever is moved out of right angular position, the side of the opening grips the rod 27. A leaf spring 33 is secured to the lever and acts against the gauge plate 28 to constantly urge the forward extremity of the lever 32 downwardly so that it will grip the rod 27 when the latter moves downwardly.

When the rod 27 is moved upwardly, it lifts the lever 32 to the right angle position and allows the rod to slide freely therethrough without raising the gauge plate 28. A finger bracket 34 projects from the gauge plate immediately above the lever 32 so that the two may be grasped by the fingers to lift the lever to the released position to allow the entire gauge plate to be adjusted or raised to the top of the rack bars.

In use, the typist suspends the sheet to be copied from the paper clamp 14 between the gauge 28 and the plate 10. She then releases the gauge plate by lifting the lever 32 and moves it to a position below the first line to be copied. When this line has been copied, she strikes the spacer bar 23 with the fingers. This causes the rod 27 to pull downwardly on the lever 32 and

move the gauge downwardly a line space so that the next line to be copied will be visible. This operation is continued to the bottom of the sheet.

The gauge plate 28 is preferably formed with a sight opening 35 below which is a letter spacing scale 36. It is preferred to view the line to be copied through this opening immediately above the scale 36 since this concentrates the vision on the line being copied. The upper edge of the gauge 28 however can be used for this purpose if desired, as it is provided with a second letter spacing scale 37. The spacing scales are indexed similarly to the scales of an ordinary typewriter so that the operator can read the line positions on these scales and set her tabular stops to correspond therewith.

A brake spring 38 is compressed between one of the brackets 29 and the adjacent pinion 31 to act as a brake against the latter to support the gauge plate in its set position.

While a specific form of the improvement has been described and illustrated herein, it is desired to be understood that the same may be varied, within the scope of the appended claims, without departing from the spirit of the invention.

Having thus described the invention, what is claimed and desired to be secured by Letters Patent is:

1. In a copy holder for typists having: a backing board; means for supporting said board in a substantially vertical position; means for clamping a sheet of paper to the face of said board; and a line gauge member extending across the forward face of said board in spaced relation thereto; means for effecting a sliding connection between the gauge member and the vertical edges of the board; a shaft extending across the rear face of said board between the extremities of said gauge member and journalled at its ends to the ends of the latter; pinion gears secured on said shaft; a rack member in mesh with each pinion gear and secured vertically on rear face of said board; a depressible spacing bar extending forwardly of said board; resilient means for holding the spacing bar in elevated position; a gauge actuating rod vertically reciprocable by said spacing bar; and means for connecting the line gauge member with the rod when the spacing bar is depressed and for releasing the rod when the spacing bar is released.

2. A copy holder for typists comprising: a backing board; means for supporting said board in a substantially vertical position; means for clamping a sheet of paper to the face of said board;

a line gauge member extending across the forward face of said board in spaced relation thereto; means for slidably mounting said gauge member at the vertical edges of said board; a shaft extending across the rear face of said board between and connected to the extremities of said gauge member; pinion gears secured on said shaft; and a rack member in mesh with each pinion gear and secured vertically on the rear face of said board; a depressible spacing bar extending forwardly of said board; a gauge actuating rod operable by said spacing bar; a gauge actuating mechanism comprising a lever, rotatably mounted on and extending from said shaft, said lever having an opening for the passage of said gauge actuating rod, said opening engaging said rod closely so that when said lever is moved at an angle to said rod, the wall of the opening will engage and grip the rod, and resilient means for biasing the lever downwardly.

3. A copy holder for typists, comprising in combination, a backing board having two parallel edges, a line gauge extending across the face thereof, means for guiding the gauge comprising a slidable connection between the ends thereof and the parallel edges of the board, a shaft extending across the board at the back thereof, bearings carried by the ends of the line gauge, the shaft being journalled in the bearings, racks secured to the rear of the board, one adjacent each of the parallel edges, pinions non-rotatably carried by the shaft for conjoint engagement with the racks, and means comprising a gauge actuating mechanism for periodically effecting a predetermined amount of rotary movement of the shaft and a corresponding movement of the line gauge.

4. A copy holder for typists, comprising in combination, a backing board having two parallel edges, a rack attached to the back thereof adjacent each edge, a line guide extending across the face of the board, the ends of the guide having alined bearings whose axes are to the rear of the racks, a shaft rotatably mounted in the bearings, pinions non-rotatably connected with the shaft for engagement and conjoint cooperation with the racks, a gauge actuating mechanism operatively associated with the shaft, the mechanism comprising a lever having an opening, a rod extending through the opening, means for reciprocating the rod, and resilient means associated with the lever for biasing it in a direction to move the line gauge downwardly.

SAMUEL FORD.
